Primary Examiner — Jack Reickel*Assistant Examiner* — Keith J Wilson(74) *Attorney, Agent, or Firm* — Muncy, Geissler, Olds & Lowe, P.C.(57) **CLAIM**

The ornamental design for a shower head, as shown and described.

DESCRIPTION

FIG. 1 is a front perspective view of a shower head according to the present invention.

FIG. 2 is a front view of the shower head of FIG. 1.

FIG. 3 is a rear view of the shower head of FIG. 1.

FIG. 4 is a left side view of the shower head of FIG. 1.

FIG. 5 is a right side view of the shower head of FIG. 1.

FIG. 6 is a top view of the shower head of FIG. 1; and,

FIG. 7 is a bottom view of the shower head of FIG. 1.

The broken line showing of a shower head represent portions of the article and forms no part of the claimed design.

1 Claim, 7 Drawing Sheets(56)
